UNITED STATES PATENT OFFICE

2,376,873

TOBACCO CURING SYSTEM

James R. Henderson, Miami, Fla.

Application June 14, 1941, Serial No. 398,154

3 Claims. (Cl. 158—36)

This invention relates to tobacco curing apparatus and is an improvement over the structure disclosed in my prior Patent Number 2,216,075 which issued September 24, 1940.

In the structure disclosed in my prior patent, the outlet of the heat from the hot air duct is adapted to be cut off when a fusible element melts at a predetermined temperature and at the same time, the fuel to the heater or burner is automatically cut off, but in this apparatus the volume of heat entering a duct and discharging into the barn cannot be finely regulated. It is, therefore, an object of this invention to provide a more simple apparatus than is disclosed in my prior patent which can be regulated from the exterior of the barn.

An object of this invention is to provide a curing apparatus of this kind wherein the flow of fuel to the burner is automatically cut off when the burner goes out so as to thereby prevent flooding of the burner.

A further object of this invention is to provide an improved means for maintaining the fuel supply under a predetermined pressure in order to insure the proper flow of fuel from the supply tank.

To the foregoing objects and to others which may hereinafter appear, the invention consists of the novel construction, combination and arrangement of parts as will be more specifically referred to and illustrated in the accompanying drawings wherein are shown embodiments of the invention, but it is to be understood that changes, variations and modifications may be resorted to which fall within the scope of the invention as claimed.

In the drawings:

Figure 1 is a horizontal section through a tobacco curing barn having a tobacco curing apparatus constructed according to an embodiment of this invention mounted therein.

Figure 2 is a vertical section taken on the line 2—2 of Figure 1.

Figure 3 is a sectional view taken on the line 3—3 of Figure 1.

Figure 4 is a sectional view taken on the line 4—4 of Figure 3.

Figure 5 is a sectional view taken on the line 5—5 of Figure 1.

Figure 6 is a fragmentary longitudinal section through the burner used with this invention.

Figure 7 is a fragmentary sectional view taken on the line 7—7 of Figure 1.

Figure 8 is a fragmentary sectional view taken on the line 8—8 of Figure 1.

Figure 9 is a fragmentary front elevation of the fuel supply tank.

Figure 10 is a fragmentary sectional view of the fuel supply line and the connection with this line of the temperature controlled operator.

Referring to the drawings, numeral 15 designates generally a tobacco curing barn which is formed with vertical side walls 16 and 17 and end walls 18 and 19. The configuration of the barn 15 herein disclosed, is conventional and it will be understood that this barn may be of any desired size including length, width and height and will be provided on the interior thereof with the conventional means for suspending the tobacco above the floor.

In order to provide a means whereby the tobacco disposed in the barn 15 may be cured through the application of heat, I have provided a heating member or oven generally designated as 20 which is adapted to be positioned exteriorly of the barn 15. The heating member 20 comprises a bottom wall 21, side walls 22, a forward wall 23 and a rear wall 24. A top wall 25 is disposed on top of the side walls 22 and the end walls 23 and 24. An inner wall 26 is disposed between the end walls 23 and 24 thereby dividing the burner housing or heating member 20 into a burner chamber 27 and a heating chamber 28. A burner, generally designated as 29, is disposed in the lower portion of the burner chamber 27 and confronts an opening 30 which is formed in the lower portion of the inner wall 26 so that the heat from the burner 29 will be ejected into the heating chamber 28. The top wall 25 of the heating member 20 is provided with an air intake opening 31 which is open to atmosphere so that cool air will be drawn into the burner chamber 27 and will mix with the heat from the burner 29 and pass into the heating chamber 28. The top wall 25 of the housing 20 is provided with an outlet nipple 32 with which a pipe or stack 33 is engaged. A damper 34 is mounted in the pipe or stack 33 and is provided with a manually operable handle 35 so that the damper 34 may be disposed in the desired open or closed position.

The housing 20 also has connected therewith an outlet pipe or nipple 36 having a damper 37 mounted therein which is provided with a handle 38 in order that the damper 37 may be disposed in the desired open or closed position. A pair of forwardly divergent branches 39 and 40 are connected at their convergent ends with the forward end of the nipple 36 and the branch 39 has a duct or pipe 41 connected therewith. A branch 40 has a pipe 42 connected therewith and the two

pipes or ducts 41 and 42 are extended through openings 43 and 44 provided in the rear end wall 19 and are disposed in a horizontal position within the interior of the barn 15. A pair of ducts or pipes 45 and 46 are connected at their rear ends with the branches 39 and 40 respectively and are extended into the barn 15 through openings 47 and 48 respectively which are formed in the rear wall 19. The pipe or duct 41 is provided with a manually operable damper 49 and the pipe or duct 42 is provided with a manually operable damper 50. These two dampers 49 and 50, positioned exteriorly of the barn 15, so that the amount of hot air passing from the branches 39 and 40 into the pipes 41 and 42 may be manually controlled from the exterior of the barn 15. The branches 45 and 46 also have positioned therein dampers 51 and 52 which are disposed exteriorly from the barn 15 to permit adjustment of these dampers without entering the barn 15. The pipes or ducts 41, 42, 45 and 46 are disposed in parallel and horizontal relation within the barn 15, being disposed closely adjacent the floor of the barn so that the heat discharged from these ducts will rise upwardly in the interior of the barn.

Each heat conducting pipe or duct has secured thereto a plurality of heat directing and regulating members shown in greater detail in Figures 3 and 4 and generally designated as 53. As shown in Figures 3 and 4 the heat outlet members are vertically adjustable in upstanding nipples or sleeves 54 which are secured to the hot air ducts in spaced apart relation. A cylindrical and vertically adjustable sleeve 55 telescopes into the nipple 54 and has its lower end extended partly into the interior of a hot air duct. The sleeve 55 is adapted to frictionally engage the interior of a nipple 54 so that it may be firmly held in its vertically adjusted position. The lower end of the sleeve 55 is provided with a baffle or by-pass member 56 by means of which a portion of the heat moving lengthwise of the hot air duct is adapted to be by-passed upwardly through the sleeve 55. A damper 57 is mounted in the sleeve 55 at a point above the upper end of the nipple 54, being mounted on a damper shaft 58 which is journaled in bearings 59 and 60 carried by the sleeve 55, and a handle 61 is fixed to one end of the shaft 58 exteriorly of the sleeve 55.

A conical hood 62 is disposed above the upper end of the sleeve 55, being supported in upwardly spaced relation to the upper end of the sleeve 55 by means of a pair of vertically disposed hood supporting arms 63 which are fixed at their upper ends to the inner surface of the hood 62. The lower ends of the hood supporting arm 63 are inwardly bent, as at 64, and removably engage in outwardly offset socket members 65 which are carried by the upper end of the sleeve 55. Through the use of the vertically adjustable air discharge members 53 the sleeves 55 may be vertically adjusted relative to its associated hot air duct so that an even amount of hot air will be discharged into the interior of the barn 15 throughout the lengths of the hot air ducts. It will, of course, be understood that the damper members 57 in each discharge sleeve 55 may be regulated to the desired position so as to regulate the quantity of air which is discharged into the interior of the barn 15 at a particular location.

There may be as many of these hot air ducts connected with the branches 39 and 40 as may be desired and if desired one or more of the hot

air ducts may be cut off by means of its associated exterior damper.

The burner 28 includes a cylindrical burner housing 66 which is mounted on a pair of standards or supporting members 67 engaging the bottom wall 21 of the housing 20. The cylindrical wall 66 is formed with a tapered forward end portion 68 confronting the tapering opening 30 in the inner wall 26 and the rear end of the housing 66 has mounted therein a rear wall 69 formed with an opening 70. An intermediate or inner wall 71 is mounted within the cylindrical housing 66 and is provided with an opening 72 which is adapted to align with a burner nozzle 73. The burner nozzle 73 is mounted rearwardly of the inner wall 71, and is formed as part of a U-shaped fuel pipe 74 which extends through an opening 75 formed in the inner wall 71 below the opening 72. A helical coil 76 is disposed in the forward chamber 77 which is positioned forwardly of the intermediate wall 71 and the particles of combustion emanating from the nozzle 73 are adapted to pass through the interior of the coil 76 so that the fuel in the coil 76 will be preheated to a substantially vaporization point before the fuel is discharged from the nozzle 73. The forward end of the coil 76 is extended through an opening 78 formed in the cylindrical wall 66 and is connected to a fuel supply pipe 79. The fuel supply pipe 79 is connected to a fuel supply tank 80 which is positioned forwardly of the heating member 20 and closely adjacent the outer side of the rear wall 19 of the barn 15. A regulating valve 81 is interposed in the pipe 79 and is positioned in the present instance closely adjacent the heating member 20. The fuel in the supply tank 80 is adapted to be initially placed under pressure by discharging air through an air valve 82 which is connected to a pipe 83. A pressure gauge 84 is interposed in the pipe 83 between the valve 82 and the adjacent wall of the tank 80. A conventional safety valve 85 is connected by means of a pipe 86 to the tank 80 in order that any excess pressure generated in the tank 80 may be automatically released.

In order to provide a means whereby a predetermined pressure may be constantly maintained in the fuel supply tank 80 I have provided a hot air duct or pipe 87 which, at its rear end, is connected to the forward wall 23 of the heating member 20, at a point below the connection of the nipple or duct 36 with the wall 23. A damper 88 is mounted in the duct 87 and is adapted to automatically regulate, as will hereinafter be described, the amount of hot air passing through the duct 87. The forward end of the duct 87 may be provided with a pair of oppositely extending branches 89 and 90 which are connected with the hot air ducts 45 and 46 respectively. The duct 87, as will be noted from Figure 2, passes partly around the tank 80 so that the heat from this duct will heat the tank 80 and the fuel contained therein.

In order to provide a means whereby the damper 88 may be automatically operated I have provided, as shown in Figure 7, a pressure operated damper operator which includes a diaphragm housing 91 which is connected with a pipe or nipple 92 communicating with the tank 80. A diaphragm 93 is mounted within the diaphragm housing 91 and a vertically extending rod 94 is fixed at its lower end to the diaphragm 93 as at 95. The rod 94 extends through an opening 96 formed in the upper half 97 of the housing 91, and is slidably connected with a vertically rock-

able lever 98. The lever 98 is formed with an elongated slot 99 in which the pivot 100 carried by the rod 94 slidably engages. One end of the lever 98 is rockably mounted on a pivot 101 carried by an upwardly extending lever supporting arm 102 which is fixed to the diaphragm housing 91. The other end of the lever 98 is connected with the operating arm 103 of the damper 88 by means of a link 104. The upper end of the link 104 engages an eye or ring 105 which is carried by the adjacent end of the lever 98. In this manner when the pressure within the fuel tank 80 exceeds a predetermined degree the diaphragm 93 will be flexed upwardly and the lever 98 raised so as to thereby move the damper 88 to a duct closing position.

In order to provide a means whereby the operation of the burner 29 may be automatically controlled so as to automatically cut off the supply of fuel from the tank 80 when the burner 29 is out I have provided a temperature operating valve structure generally designated as 106 which is interposed in the pipe 79 between the manually operable valve 81 and the burner 29. The cut-off valve structure 106 includes a housing 107 having a valve seat 108 with which a poppet valve member 109 is adapted to be associated. The poppet valve member 109 has secured thereto a valve stem 110 which is disposed on opposite sides of the valve member 109 and is slideable at its upper side through a partition wall 111 dividing the upper portion of the housing 107 into a fuel chamber 112 and a diaphragm chamber 113. A lower guiding wall 114 is disposed in upwardly offset relation to the bottom wall 115 of the housing 107 and a reduced cylindrical housing 116 extends downwardly from the bottom wall 115. A spring 117 may be disposed about the lower portion of the valve stem 110 and engage at its upper end against the under side of the guiding wall 114 and at its lower end against a nut or abutment 118 fixed to the stem 110. A valve compressing spring 119 is disposed in the housing 116 and bears against the abutment 118 and is tensioned by means of a spring tension rod 120 having a head 121 at its upper or inner end. A threaded bolt or shaft 122 is fixed to the lower end of the rod or stem 120 and is threaded through a gland 123 engaging the lower end of the housing 116. The valve structure 106 includes a cap 124 formed with a flange 125 which is secured by fastening devices 126 to a flange 127 carried by the upper end portion of the housing 107 above the wall 111. A diaphragm 128 is fixed by fastening devices 129 to the upper end of the stem 110 and is interposed between the two flanges 125 and 127. A liquid conducting pipe 130 is connected at one end to the cap 124 and is then extended downwardly and passed through an opening 131 formed in a boss 132 carried by a bend or branch 133 forming a part of the fuel line 79. The pipe 130 is then extended axially as at 134 into the interior of the branch 133 and terminates in the forward convolution 135 of the preheating coil 76. The terminal end of the pipe branch 134 within the convolution 135 is permanently closed and preferably a liquid, in the form of alcohol or the like, is adapted to be positioned in the pipe 130 and the branch 134 and this liquid is also positioned in the liquid chamber 136 formed between the cap 124 and the upper side of the diaphragm 128. As the liquid in the pipe 130 becomes heated and expands the diaphragm 128 will be flexed downwardly so as to hold the valve member 109 in an open position.

In order to start the operation of the burner 29 the spring 119 is relieved of tension by unthreading the spring tensioning member 122 so that the spring 117 will move the valve member 109 downwardly to the desired open position. After the burner is in operation for a short time the liquid in the pipe 130 and in the chamber 136 will become heated so that the diaphragm 128 will thereby be flexed downwardly through expansion of the liquid and at this time the spring tensioning member 122 may be returned to the spring tensioning position so that if the burner 29 should go out and the liquid in the pipe 130 the spring 119 will then automatically return the valve member 109 to a cut-off position on the seat 108.

In the use and operation of this device, the fuel in the tank 80 initially is placed under the desired pressure by discharging air under pressure through the air valve 82. The cut-off valve 81 may be opened and the spring tensioning member 122 may be moved to a position to relieve the tension on the spring 119 and permit the spring 117 to move the valve member 109 to an open position. The fuel, at the end of the burner nozzle 73, may then be ignited and the heat from the nozzle 73 will pass through the convolutions of the coil 76 thereby heating the fuel in the coil 76 to a substantially vaporization point. The burner 29 will draw into the heating chamber 28 air from the burner chamber 27 which enters the burner chamber 27 through the intake opening 31. At the start of the operation of this heating apparatus the initial pressure in the tank 80 will flex the damper regulating diaphragm 93 upwardly so as to hold the damper 88 in the duct 87 in a closed position. The heat from the heating chamber 28 will thus be cut off from the duct 87. The heat, however, in the chamber 28 will pass outwardly through the outlet duct or nipple 36 and then enter the branches 39 and 40 and the several heat conducting ducts 41, 42, 45 and 46. The vertical adjustment of the discharge sleeves 55 carried by the heat conducting ducts will determine the amount of heat which is by-passed from the ducts into the interior of the barn. In addition to the adjustment of the discharge sleeves 55 to determine the amount of heat which is by-passed into the different portions of the barn, each sleeve 55 may have its associated damper 57 adjusted to the desired position in order to further regulate the amount of hot air discharged therefrom.

With a tobacco curing apparatus as hereinbefore described, it is possible to operate the burner structure without undue attention thereto as, if the burner should accidentally go out, the fuel line to the burner will be automatically cut-off by means of the temperature operated cut-off valve structure 106.

What I claim is:

1. In a tobacco curing apparatus, an air heating member, a burner in said heating member, a fuel pressure tank connected with said burner, a hot air duct connected with said heating member and engaging partly about said tank for heating the fuel in said tank and increasing the pressure therein, a damper in said latter duct, and pressure operated means connected with said tank and said damper for operating said damper in accordance with the pressure formed in said tank resulting from expansion of fuel in the latter.

2. In a tobacco curing apparatus, an air heat-

ing member, a burner in said heating member, a fuel pressure tank connected with said burner, a hot air duct connected with said heating member and engaging partly about said tank for heating the fuel in said tank and placing the fuel under a predetermined pressure, a damper in said latter duct, a diaphragm structure connected with said tank, and means connecting said diaphragm structure with said damper for adjustment of said damper in accordance with the pressure within said tank.

3. In a tobacco curing apparatus, an air heating member, a burner in said heating member, a fuel tank connected with said burner, means

for placing the fuel in said tank under pressure, said means including means whereby air under pressure may be discharged into said tank, a hot air duct communicating with said heating member, a tank heating duct communicating with said heating member and said first duct and at least partly encompassing said tank whereby to increase the pressure in said tank, a damper in said tank heating duct, and a pressure operated member connected to said tank and to said damper whereby to regulate the opening and closing of the damper in accordance with the pressure in said tank.

JAMES R. HENDERSON.
